UNITED STATES PATENT OFFICE.

THOMAS M. ROYAL, OF PHILADELPHIA, PENNSYLVANIA.

PAPER FOR WIPING ENGRAVED PRINTING PLATES.

Application filed April 22, 1927. Serial No. 185,680.

In the art of printing from engraved printing plates the ink is applied by suitable means to the faces of the plates, the required amount of ink being deposited in the 5 engraved lines upon the surfaces of the plates. The ink having been applied it is necessary that it be removed from the surfaces of the plates outside of the engraved lines before the act of printing is performed; 10 that is, before a sheet of paper is placed upon a plate and pressure applied thereto for the purpose of effecting the transfer of the ink from the engraved lines onto the paper.

15 For the purpose of effecting removal of the ink from the surface of a plate outside of the engraved lines thereon the practice is to feed a web of wiping paper through a printing press in proper relation to the 20 path of travel of said plate from the point where ink is applied thereto and deposited in the engraved lines thereon to the point where the printing is performed. The surface of the plate as it travels from the inking 25 position to the printing position rubs against the opposing side of the wiping web of paper whereby removal of the ink from the surface thereof, except that which has been deposited in the engraved lines, is effected. 30 The web of paper as it is fed through the printing machine is of necessity subjected to more or less stretching tension. Heretofore the paper has been employed or used without previous or special 35 treatment to render the same more efficient in removing the ink from the surfaces of the plates, in consequence of which it has been necessary not only to employ relatively heavy paper but to subject the same to relatively 40 great stretching tension and the application of the same with relatively great pressure against the surface of the plate. The weight of the paper heretofore used, and now in general use, has ranged from 45 fifty-five to sixty pounds per ream, but when paper without previous or special treatment is used it is necessary to subject it to such pressure and tension that not infrequently the sheets or webs as used have been broken 50 thus causing delay and waste of paper. As a result of the relatively great pressure between the wiping sheets of paper and the plates a relatively great amount of friction has been developed between the sheets and 55 the surfaces of the plates. In consequence of this wearing off of the surfaces of the

plates has been rather rapid, thereby unnecessarily decreasing the period or periods during which the plates may be used satisfactorily.

Another objection to wiping paper of ordinary untreated stock has been that the ink enters into the pores of the same and also hardens quickly so that it may not in practice be removed, consequently used wiping 60 paper has had but very little value for resale or other purposes.

It will be apparent that if a paper may be treated in such manner that much lighter stock may be employed and in a manner to 65 obviate the objections and disadvantages heretofore indicated a substantial advance in the art will have been achieved. I have found that paper treated with a suitable oil is given characteristics whereby it may 70 be used as a wiping paper for removing the ink from engraved printing plates to very great advantage.

Among the oils suitable for use in the 75 treatment of paper to provide a wiping 80 paper embodying the invention I may mention mineral oil, such as residuum oil, cylinder oil, engine oil, motor oil, paraffin oil, neutral oil, spindle oil, technical white oil, petrolatum, petrolatum grease, etc., whether 85 they be derived from paraffin base, mixed base or crude asphaltic base, and also animal and vegetable oils, fixed and volatile. These latter oils may be used either alone or in admixture with one or more of the 90 mineral oils.

The mineral oils mentioned may be used in the finished or what is known as the "fully refined" state, or they may be used while in the intermediate stage of processing or manufacture; that is, before they are 95 "fully refined". The fixed oils are preferable but volatile oil may be employed.

Some of the objects of my invention are, 100 to provide a paper of a character such that sheets of less thickness than heretofore employed may be used; that is, sheets of a thickness such that the weight thereof will range around forty pounds per ream; to provide paper of a character such that it will 105 effect a cleaner wiping of the surfaces of the engraved printing plates than heretofore has been practical; to provide a paper of a character such that the areas upon the surface thereof onto which all of the ink from the plate is removed are substantially narrower or less than the corresponding areas 110

on the surfaces of papers as heretofore used; to provide a paper such that complete and satisfactory removal of the ink from the surfaces of the plates may be effected by the employment of less pressure between the plates and the sheets than heretofore has been required, thereby reducing the friction between the plates and the paper and also reducing the stretching tension upon the paper; to provide a sheet of a character such that it will not remove any of the ink from the engraved lines upon the plate, thereby leaving the entire amount of the ink in said engraved lines to be applied to the paper in the printing operation; and also to provide paper of a character such that the ink may be removed from the surface thereof so that the sheets or webs may be reused for wiping the ink from engraved printing plates.

20 In the course of the detailed description of the invention which follows other objects and advantages of the invention will be indicated.

In addition to illustrating in the drawing 25 a sheet of paper embodying the invention I have illustrated a machine of the type in which wiping paper is employed and have shown a web of wiping mounted upon and extending through the machine and having 30 a portion thereof in proper relation to an engraved printing plate the surface of which is to be wiped at intervals.

In the drawing:

Fig. 1 is a transverse vertical sectional 35 view in diagrammatic form of a machine in which engraved printing plates and wiping paper are employed;

Fig. 2 is a plan view of a fragmentary portion of a sheet or web of paper embodying my invention indicating the width thereon of the ink removed from printing plates of predetermined width;

Fig. 3 is a view in transverse section of the web or sheet of paper shown in Fig. 2;

45 Fig. 4 is a plan view of a fragmentary portion of a web or sheet of paper of the kind heretofore used and showing the width of the ink thereon as removed from a printing plate of the same width as that presupposed in connection with Fig. 2; and

50 Fig. 5 is a view in transverse section of the web or sheet of paper shown in Fig. 4.

Figs. 3 and 5 have been given for the purpose of comparison between the thickness of a wiping sheet as heretofore used and that of a wiping sheet embodying my invention.

In Fig. 1 of the drawing I have shown an engraved printing plate 1 mounted upon a bed or carrier 2 supported to be reciprocated back and forth between the ink applying means indicated at 3 and the printing position indicated at 4. The ink is adapted to be applied to the surface of the printing plate 1 by means of a roller 5 mounted upon 60 oscillatable levers or arms 6 in known man-

ner. The wiping web or sheet of paper 10 is in the form of a roll 11 revolubly supported upon a shaft 12. The web extends from the roll 11 underneath a guide roll 13, between rolls 14 and 15, over a guide roll 16, 70 underneath a pressure bed 17 and from the latter to a rotatable shaft 18 about which the used web or sheet is wound. The pressure bed is adjustable vertically to vary the pressure with which the portion of the sheet 75 thereunder is caused to contact with or engage the top surface of the printing plate 1 upon the reciprocating bed or support 2.

In the operation of the press the pressure bed 17 is reciprocated through a short distance vertically so that upon the return movement of the printing plate 1 from the printing to the inking position it does not contact with the underneath opposing surface of the portion of the web or sheet 10 80 underneath the pressure bed 17. Prior to the return movement of the printing plate from the inking position to printing position the pressure bed 17 is lowered so that in its return movement the top of the plate 1 is pressed and wiped against the under side of the portion of the web underneath the pressure bed 17. Upon reference to Fig. 1 it will be seen that the forward or right hand edge of the surface of the plate 1 first contacts with the portion of the web underneath the pressure bed 17 along a line in alinement with the left hand edge of the said bed. As already indicated, in machines of the character of that suggested in 100 Fig. 1 of the drawing (which machines are well known and in general use) the pressure bed 17 is adjustable in order to vary the pressure of the section or portion of the wiping paper underneath the same against 105 the opposing upper surface of the printing plate 1. Such adjustment and variation of pressure may be in a direction to increase the stretching tension upon the web. In the use of paper of the character heretofore employed this pressure and tension have been relatively great, in consequence of which the webs have not infrequently broken, thus entailing a loss of time and of 110 paper. Furthermore, as already indicated, such increase of pressure increases the friction between the contacting surfaces of the paper and the plate, thereby causing relatively rapid wearing away of the latter.

The characteristics of webs or sheets of 120 paper which have been treated with oil of the character previously indicated in accordance with my invention are such that the ink is completely removed from the surfaces of the plates surrounding the engraved 125 lines thereon even though the pressure between the plate and the sheet is very much less than that which has been necessary heretofore when paper without special treatment has been used. Application of the oil 130

to the paper is effected by causing the same ink to be drawn more or less slowly through a body of oil of a character previously indicated at ordinary room temperature and at normal atmospheric pressure. The surfaces of the paper are fairly well impregnated with the oil but complete saturation of the paper is not desirable although permissible.

10 It has been found that when paper so treated is used for the removal of ink from the surfaces of plates the area of the surface of the paper necessary to completely remove the ink is substantially less than when paper of ordinary stock is used. For instance, to give a concrete example, it has been found that for the removal of the ink from a plate having a width of four and a half inches the ink band or smear produced upon a sheet embodying my invention is approximately four inches wide and that the successive bands or smears are separated approximately one and a half inches; whereas if untreated paper as heretofore used is employed the bands or smears of ink are approximately five inches wide and it is necessary to separate these bands or locate them approximately two and one half inches apart. This is due to the fact that in the latter case the smear marks extend over a substantially wider space than is the case when paper embodying my invention is employed.

35 These dimensions would vary if plates of different widths were used,—the ink removed from wider plates covering greater areas of the surface of the sheets and that removed from narrower plates covering less areas upon the said sheets.

40 In Fig. 2 of the drawing I have illustrated at 19 the widths and as far as possible the appearance of the bands of ink as removed upon a sheet of wiping paper 20 embodying my invention, and have also indicated the spaces between successive bands of removed ink.

45 In Fig. 4 I have illustrated at 21 the bands of ink removed from the surfaces of printing plates by means of a sheet of untreated paper 22, such as heretofore has been in use, and have also indicated the width of the spaces between successive bands. In both cases the sheets of paper 20 and 22 were employed for the removal of the ink from printing plates having a width of four and a half inches. In other words, the conditions under which the two sheets 20 and 22 were used were identical in every respect. It will be seen, therefore, that a great saving of paper is effected by reason of the fact that a much smaller area of the treated paper is required to effect removal of the ink than is required when untreated paper is used. Not only is a smaller area of paper required for the removal of the

and areas when treated paper is employed, but the removal of the ink is more completely effected so that the surfaces of the plates are cleaner than when untreated paper, such as heretofore has been used, is employed. One reason for this is that the treated paper has had imparted to it a characteristic whereby its adhesive qualities have been improved as compared with the untreated paper heretofore used. Another reason appears to be that the surfaces of the printing plates become covered with a thin film of oil the presence of which renders the ink more readily removable.

80 Another advantage which may be mentioned as being incident to my invention is that the employment of sheets embodying the same enables the use of water inks without the "picking" of color from a previously run color in operations in which two or more colors are employed.

85 In Fig. 3 I have shown a transverse section of a sheet 20 embodying my invention and in Fig. 5 I have shown a similar section of a sheet 22. These two figures have been provided for the purpose of indicating the relative thickness of treated or oiled sheets embodying my invention and the untreated sheets as heretofore employed as wiping sheets for the removal of ink from the surface of intaglio printing plates.

90 It will be seen that by my invention, which enables the use of sheets substantially thinner than those which heretofore it has been possible to use, I am enabled to bring about a substantial saving in the quantity of paper as originally required, the difference being in the proportion by weight of approximately forty pounds per ream and fifty-five to sixty pounds per ream. In addition to a saving in this respect there is also a substantial saving due to the fact that smaller areas of the treated paper suffice for the removal of the ink from the plates than are required when untreated paper, as heretofore employed, is used; and also that the areas of the treated sheet upon which the ink is removed may be located more closely together than is practical when untreated paper, as heretofore used, is employed.

100 A further saving results because it is not necessary to maintain the treated paper under as great a stretching tension or to apply it to the surface of the printing plates with as great a pressure as in the case of untreated paper, whereby there is less frequent breakage of the web and whereby also there is less friction between the paper and the surfaces of the plates and consequently less wear upon the latter. Moreover, a substantial saving, from a commercial stand point, results from the fact that the storage space required to care for the supply necessary to

be carried in stock is substantially less than is or would be required to carry in stock the same amount of yardage of untreated paper of the character of that heretofore in use; also a less amount of pulp is required for the production of a given yardage of paper satisfactory for use if the same is treated in accordance with my invention than would be required if the paper manufactured from such pulp were to be used in untreated state as heretofore has been the case.

It will be seen that by my invention I have provided a wiping paper for removing the ink from intaglio printing plates having characteristics which render it of marked advantage over the wiping paper heretofore in use.

Having thus described my invention, what I claim and desire to secure by Letters Patent is:

1. Oiled wiping paper for the removal of ink from printing plates.
2. Wiping paper for the removal of ink from the surfaces of printing plates the surfaces of the paper being covered with oil which is liquid at room temperature.
3. Wiping paper for the removal of ink from the surfaces of intaglio printing

plates, which paper is impregnated with a non-volatile oil.

4. Wiping paper for the removal of ink from the surfaces of printing plates which is partially saturated with oil whereby its adhesive qualities with respect to the ink on such plates is increased.

5. Wiping paper for the removal of ink from printing plates the surfaces of which paper are impregnated with mineral oil.

6. Wiping paper for the removal of ink from the surfaces of printing plates, which paper has been treated with a suitable oil which is liquid at ordinary room temperature.

7. Oiled paper for the removal of ink from the surfaces of printing plates, the oil employed for oiling the same being preferably mineral oil which is liquid at ordinary room temperature.

8. Wiping paper for the removal of ink from printing plates the surfaces of the paper being impregnated with a mixture of mineral and other oils.

In testimony that I claim the foregoing as my invention, I have hereunto signed my name this 20th day of April, 1927.

THOMAS M. ROYAL.
